Attorney

UNITED STATES PATENT OFFICE.

BENNIE R. SMITH, OF EDWARDS, MISSOURI.

RAILROAD-CROSSING SIGNAL.

Application filed February 14, 1924. Serial No. 692,757.

To all whom it may concern:

Be it known that I, BENNIE R. SMITH, a citizen of the United States, residing at Edwards, in the county of Benton and State 5 of Missouri, have invented certain new and useful Improvements in Railroad-Crossing Signals, of which the following is a specification, reference being had to the accompanying drawings.

- 10 This invention relates to an improved signal for use in connection with the crossing at a railroad and one object of the invention is to provide a signal which is so constructed that when a train is approaching 15 a crossing a bell may be sounded and a semaphore arm swung vertically so that any one approaching a railroad will be warned of an approaching train by a visible signal and also by an audible signal.
- 20 Another object of the invention is to so construct this signal that the semaphore arm and the bell sounding striker may be both actuated from a shaft which is rotatably mounted and caused to rotate by an actuating lever mounted for engagement by the 25 wheels of a train.

Another object of the invention is to provide a drive shaft which is formed of sections connected by a spring so that when the 30 wheels of a train engage the actuating lever to impart rotary movement to this drive shaft the spring may serve as means for absorbing the force of the blow received and thereby prevent possible danger of breakage 35 of parts of the device.

Another object of the invention is to provide a signal of this character which may be mounted in operative relation to the track and cross road and have the operating 40 elements protected from exposure to the weather so that they will not be injured by moisture or by snow or ice.

This invention is illustrated in the accompanying drawings, wherein:-

45 Figure 1 is a perspective view showing the danger signal in position for use.

Figure 2 is an enlarged fragmentary view showing a portion of the signal partially in elevation and partially in section.

50 Figure 3 is a fragmentary view showing the train engaged portion of the signal partially in top plan and partially in section.

Figure 4 is a view showing the train engaged portion of the signal in elevation.

55 This improved signal is for use in giving a warning when a train is approaching

a cross road and, therefore, at the cross road there has been provided a standard or post 1. A semaphore arm 2 is pivotally connected with this post and has one end portion provided with a flag 3 upon which may be displayed a suitable warning such as the word "Stop". At its other end the arm or lever 2 is provided with a weight 4 serving as a counterbalance weight to permit the arm to be easily swung vertically. This arm will be pivotally connected with the post 1 in such a position that when it swings downwardly its flag carrying end portion will move transversely across the 70 road thereby permitting the flag to be readily seen by persons approaching the railroad.

Upon the lower end portion of this post there has been provided a box or housing 5 having openings 6 and 7 provided in its top or upper wall. A pitman rod 8 is pivotally connected with the arm 2 and has its lower end portion extending through the opening into the housing 5. A bell 9 is mounted upon the post and is to be struck by a striker 10 which is pivotally mounted in a substantially vertical position and extends through the opening 7. When the striker is brought into engagement with the bell an audible warning will be given and at the same time the pitman 8 will be reciprocated vertically so that swinging movement will be imparted to the semaphore arm and a visible warning given.

In order to impart movement to the striker 10 and pitman 8 there has been provided a driven shaft 11 which is rotatably mounted in a tubular casing 12 and has one end portion extending into the housing 5. At its 95 inner end the shaft 11 carries a head which is in the form of a disc 13. This disc 13 carries a pitman engaging pin 14 and is further provided with striker engaging pins 15. It will be readily seen that as the 100 driven shaft 11 rotates the pins 15 will be brought into engagement with the lower end of the striker 10 so as to impart movement to this striker and cause the striker to ring the bell as the disc rotates. It will be 105 further noted that as this disc rotates the pitman will be moved vertically to impart the desired oscillating movement to the semaphore arm.

The tubular casing 12 extends longitudinally of the track and is supported, as shown at 16. The driven shaft may be

formed as a single length of rod or in any number of pieces suitably connected to turn as a single unit when the device is used in connection with a straight length of track.

5 When the signal is to be used at a point where the track is curved the shaft 11 may have certain of its sections connected by a universal joint positioned in a pocket 17 provided intermediate the length of the casing 12. As many of these universal joints may be provided as necessary. At the opposite end of the casing 12 from the housing 5 there has been provided a gear housing 18 and the driven shaft 11 extends into this 15 housing 18 and carries a bevel gear 19 which meshes with a larger bevel gear 20 carried by the drive shaft 21. This drive shaft 21 extends from the housing 18 through a casing 22 and this drive shaft will be formed 20 in two sections, the adjacent ends of which are connected with a spring 23. It will, therefore, be seen that when the drive shaft is rotated the spring may serve as a shock absorber to prevent damage to any parts of 25 the mechanism.

This drive shaft extends to a point adjacent one of the rails of the track and in order to impart rotary movement to the drive shaft there has been provided a longitudinally curved actuating lever 24 which is pivotally connected with the ear 25 of a base plate 26 secured upon the ties and disposed longitudinally of the track. A pawl 27 is pivotally connected with this lever 24 intermediate its length and is yieldably held in an operative position by a spring 28 so that the pawl will be held in engagement with a ratchet wheel 29 secured to the end of the drive shaft. Therefore, as the 40 lever moves up and down the pawl, by engagement with the teeth of the ratchet wheel, will intermittently impart rotary movement to the drive shaft. It is desired to prevent the spring from causing the 45 outer end portion of the drive shaft to have retrograde rotary movement and, therefore, there has been provided a latch 30 which is pivotally connected with the base plate and yieldably held in engagement with the 50 teeth of the ratchet wheel. In order to normally hold the lever 24 in an elevated position there has been provided a spring 31 which is positioned about a pin 32 pivotally connected with the lever 24 and extending 55 through an opening in the base plate 26. The lower end of this spring engages the base plate and the upper end engages the lever 24 and, therefore, the lever will be yieldably held in the raised position. By 60 properly adjusting the nut of the pin 32 the upward movement of the lever may be controlled and this lever prevented from extending above the rail beyond a desired amount.

65 When this apparatus is in use it is set

up, as shown, with the lever 24 extending longitudinally of the track and the post 1 mounted near the cross road leading to the track. When a train approaches the road the wheels will pass over the lever 24 and as each wheel passes over this lever it will be moved downwardly against the action of the spring 31 and then moved upwardly after the wheel has passed over the lever. During the downward movement the pawl 27 will engage the ratchet 29 to impart rotary movement to the ratchet and drive shaft. The spring 23 will be wound to a certain extent by the initial rotation of the outer end portion of the shaft 22 and as 70 the pawl 30 prevents the outer end portion of this shaft from being turned in a retrograde direction by the spring, the spring must exert its turning movement upon the inner end portion of the shaft. Of course 75 the entire shaft will to some extent be turned as a single unit when the lever moves downwardly but the outer end portion, by being connected with the spring, will cause the spring to be wound and thereby permit 80 the spring to absorb the force of the blow delivered to the ratchet and prevent danger of breakage of the teeth of the gears 19 and 20 or breakage of the pins 15 by excessive force. As each wheel passes over the lever 85 additional rotary movement will be delivered to the drive shaft and through the gears 19 and 20 to the driven shaft. The driven shaft will therefore be rotated for as long as the wheels of the train are passing 90 over the lever and during this rotation of the driven shaft a striker will be operated to sound the bell and the semaphore arm, together with its warning flag 3, will be swung vertically to attract attention. 100 It will therefore be seen that there has been provided a signal which will operate very effectively as a visible and an audible signal to warn people that a train is approaching. It will be further noted that by the 105 construction shown the signal may be readily applied and when in position for use will be protected from exposure to the weather so that ice and snow cannot interfere with proper operation thereof. 110

Suitable bearings may be made use of wherever necessary so that the various shafts may turn easily.

What is claimed is:—

1. A railroad signal comprising a visible signal mounted for oscillating movement, an audible signal, a striker for the audible signal, a driven shaft, a head carried by the driven shaft, pins extending from the head for engaging the striker and imparting 120 operative movement to the same when the driven shaft is rotated, a pitman pin extending from the head, a pitman rod connected with the pivot pin and visible signal 125 to impart oscillating movement to the same 130

during rotation of the driven shaft, and train actuated means for imparting rotary movement to the driven shaft.

2. A signal of the character described comprising a support, a semaphore arm pivotally connected with said support, a signal bell, a pivotally mounted striker for the signal bell, a driven shaft, a head carried by the driven shaft, abutments carried by the head for engaging the striker and imparting operative movement to the striker during rotation of the driven shaft, a pitman rod pivotally connected with the head and semaphore arm for imparting oscillating movement to the semaphore arm during rotation of the driven shaft, and train operated means for imparting rotary movement to the driven shaft.

3. A danger signal comprising warning means, operating means for the warning means including a rotatably mounted driven shaft for extending longitudinally of a track, a drive shaft, means for transmitting rotary movement from the drive shaft to the driven shaft, the drive shaft being formed in sections positioned in end to end relation to each other, spring means connected with the adjacent ends of the sections

of the drive shaft, and train actuated means for imparting rotary movement to one of the portions of the drive shaft.

4. A danger signal comprising warning means and actuating means for the warning means including a rotatably mounted drive shaft formed in sections in end to end relation to each other, a coil spring positioned about the drive shaft and having its ends connected with the adjacent ends of the drive shaft sections, a ratchet wheel carried by one of the sections of the drive shaft, a support, a lever pivotally connected with the support and adapted to be moved downwardly by the wheels of a train passing along a track, spring means yieldably holding the lever against downward movement, a pawl pivotally connected with the lever and engaging the teeth of the ratchet wheel to impart rotary movement to the ratchet wheel and drive shaft section carrying the same when the lever moves downwardly, and a latch engaging the pawl to prevent retrograde rotation thereof by the springs.

In testimony whereof I hereunto affix my signature.

BENNIE R. SMITH.
